UNITED STATES PATENT OFFICE.

OLOF F. SWANSON, OF CHICAGO, ILLINOIS.

DOOR-LOCK.

1,172,846.

Specification of Letters Patent.

Patented Feb. 22, 1916.

Application filed December 8, 1914. Serial No. 876,106.

To all whom it may concern:

Be it known that I, OLOF F. SWANSON, a citizen of the United States, and a resident of the city of Chicago, county of Cook, and 5 State of Illinois, have invented certain new and useful Improvements in Door-Locks, of which the following is a specification.

My invention relates to improvements in door locks, and has for its object the production of door locking mechanism which 10 will be of improved construction, and efficient in operation.

Other objects will appear hereinafter.

The invention consists in the combinations 15 and arrangements of parts hereinafter described and claimed.

The invention will be best understood by reference to the accompanying drawings forming a part of this specification, and in 20 which,

Figure 1 is a front elevation of a door equipped with locking mechanism embodying my invention, Fig. 2 is a section taken on line $x-x$ of Fig. 1, Fig. 3 is an enlarged 25 front elevation of a portion of the locking mechanism with the cover, of the housing shown, removed, Fig. 4 is a section taken on substantially line $y-y$ of Fig. 3, and Fig. 5 is a perspective view of one of the pivoted 30 keepers included in the construction.

The preferred form of construction, as illustrated in the drawings comprises a hinged door 1 provided at its free edge with a door lock 2 of conventional construction 35 which is embedded or mortised therein in the usual manner. The lock 2 is provided with a rotatably mounted key-actuated barrel 3 which is operatively connected with the bolt 4 of said lock so that upon rotation of 40 said barrel, said bolt will be moved to or from locking position. Coöperating with the lock 2 are also handles or door knobs 5 which are operatively connected with the latch 5' in the usual manner.

Provided upon the inner side of the door 1 are two vertically extending locking bolts 6 which are shiftably mounted in guides 7 for movement into and out of engagement 50 with sockets 8 provided at the upper and lower edges of the door, as clearly shown in Figs. 1 and 2. The inner ends of the locking bolts 6 enter the upper and lower sides of a rectangular housing 8 secured to

the inner side of the door adjacent the lock 2. Said ends of said locking bolts are connected with bars 10 arranged in the housing 9 and shiftably mounted in guide members 11. The arrangement is such, as will be seen, that movement of locking bolts 6 into and out of locking position is effected 60 through shifting of bars 10. Said shifting of said bars is effected by means of a pair of oppositely projecting oscillatory arms 12 which are secured to a spindle 13 rockingly mounted in the housing 9. The outer ends 65 of arms 12 engage with slots 14 provided in the adjacent edges of bars 10, the arrangement being such that, upon oscillation of said arms, the same, through engagement with the slots 14, will shift the bars 10 in a 70 direction dependent upon the direction of oscillation of said arms, it being clear that when said arms are oscillated in a clockwise direction, the locking bolts 6 will be moved to locking position, and that when said arms 75 are oscillated in a counter-clockwise direction, said locking bolts will be moved to unlocking position.

The locking bolts 6 are held in locking or unlocking positions by means of 80 tumblers 15 which are pivotally mounted at 16 within the housing 9. Each of said tumblers 15 is provided with an upstanding ear 17 adapted for engagement with notches 18 and 19 provided in the adjacent side of 85 the corresponding bar 10. The arrangement is such that, when the locking bolts 6 are in locking position, the ears 17 will engage with the notches 18 to hold said locking bolts in this position and, when said locking bolts are in unlocking position, the ears 17 will engage with the notches 19 and thus 90 serve to hold said bolts in this position. Helical compression springs 20 coöperate with each of the tumblers 15 to normally 95 hold the same in operative relation with the bars 10. Said tumblers 15 are, however, so arranged that, upon rocking of the arms 12 into engagement with the notches 14, said arms will engage against the inner longitudinal edges of said tumblers and thereby 100 serve to rock said tumblers to releasing position before the shifting of the bolts 10 takes place. This rocking of the tumblers 15 to releasing position is clearly shown in dotted 105 lines in Fig. 3.

The inner end of the spindle 13 projects through an opening 21 provided in the adjacent side of the door 1 to engagement with the adjacent end of the barrel 3 of lock 2, 5 said spindle 13 being arranged coaxial with said barrel. The inner end of said spindle is provided with a tongue 22 which releasably engages with a corresponding slot 23 provided in the adjacent end of the barrel 10 3, thus operatively connecting said bolt and spindle and whereby, upon rotation of barrel 3, through an engagement therewith of a key, the bolts 4 and 6 will be simultaneously actuated in order to simultaneously 15 lock or unlock the door at all three points, namely at the center and lower and upper edges thereof. The outer end of spindle 13 is provided with a knob 24 for effecting manual rotation thereof or to facilitate engagement of the tongue 22 of said spindle with the slot 23 of the lock barrel 3 in the installation or attachment of the locking mechanism.

While I have illustrated and described the 25 preferred form of construction for carrying my invention into effect, this is capable of variation and modification without departing from the spirit of the invention. I, therefore, do not wish to be limited to the 30 precise details of construction set forth, but desire to avail myself of such variations and modifications as come within the scope of the appended claim.

Copies of this patent may be obtained for five cents each, by addressing the "Commissioner of Patents, Washington, D. C."

Having described my invention what I claim as new and desire to secure by Letters 35 Patent is:

In a lock, the combination with a door, of a locking mechanism therefor comprising a key-actuated rotatable barrel mounted in said door; a pair of locking bolts shiftably 40 mounted on said door for movement in opposite directions thereon; means for shifting said bolts, said means comprising a pair of shiftably mounted bars connected with said bolts adapted, when actuated, to actuate 45 said bolts; a pair of oscillatory arms arranged between and engaging with said bars for actuating the latter; a rotatably mounted spindle carrying said arms arranged coaxial with said barrel; a slot and 50 tongue connection between said spindle and said barrel; and a tumbler coöperating with each of said bars adapted normally to yieldingly engage therewith to lock the corresponding bar at its respective terminals of 55 movement, said arms, when rocked to actuate said bars, automatically engaging with said tumblers to move the same to releasing position, substantially as described.

In testimony whereof I have signed my 60 name to this specification in the presence of two subscribing witnesses.

OLOF F. SWANSON.
